VENETIAN BLIND

Donald J. Croxen, 15608 Florwood Ave., Lawndale, Calif.

Filed May 8, 1958, Ser. No. 733,935

2 Claims. (Cl. 160—174)

This invention has to do with Venetian blinds and particularly with Venetian blinds in which the individual slats are S-shaped in cross section.

Venetian blinds having S-shaped slats have certain advantages over those of other shapes. However, a disadvantage of this type of blind has been that heretofore, as conventionally made, it is not completely closable to provide a substantially light-tight screen for the window where this is either required or desired.

An object of my invention is to provide a novel construction for Venetian blinds having S-shaped slats which permits the blind to be completely closed and thereby afford a substantially light-tight barrier at the window.

A further object of the invention is to provide a construction wherein the individual slats are shaped and recessed in a manner to accommodate the lift cord and the suspension tapes when the slats are tilted to closed position, whereby the slats may be fully closed.

Still another object is to provide a construction of the type indicated which incorporates integral reinforcing means in the region of the recessed portions of the slats.

Another object is to provide a blind construction of the type indicated in which the individual slats can be readily fabricated.

A further object is to provide a construction of reinforcement suitable for various types of slats.

A still further object is to provide a novel means incorporated in Venetian blind slats for causing the same to releasably engage each other in fully tilted position.

These and other objects will be apparent from the drawing and the following description. Referring to the drawing:

Fig. 1 is a fragmentary perspective view of the outer side and one end of a Venetian blind assembly embodying the invention;

Fig. 2 is a perspective view of three of the slats and the two lift cords;

Fig. 3 is an enlarged, fragmentary sectional view on line 3—3 of Fig. 1;

Fig. 4 is an enlarged fragmentary sectional view in the same plane as the slats in closed position and the supporting tapes omitted;

Fig. 5 is a fragmentary sectional plan view on line 5—5 of Fig. 3;

Fig. 6 is sectional view on line 6—6 of Fig. 5; and

Fig. 7 is a view similar to Fig. 5 but showing a modified form of the invention.

More particularly describing the invention, numeral 11 designates a valance box or the like which is adapted to be mounted in a building adjacent the upper margin of a window, the box being shown as having end members 12 and side members 13. The Venetian blind assembly includes a plurality of slats 15 which are suspended upon supporting tapes 16 and 17 and cross or ladder tapes 18 extending therebetween. The latter are usually staggered so that alternate ones are on opposite sides of the lifting cords. The supporting tapes are each attached at

2

their upper end to rotatable members 20 carried on a shaft 21 in the valance box. Customarily operating cords are provided for tilting the slats by manipulation of the supporting tapes. However, these have not been shown and in this connection it should be noted that such operating cords would be positioned on the room or inside of the blind assembly, and that in Figs. 1 and 2 the views show the outer side of the assembly.

The blind assembly is also customarily provided with lift cords 22 which pass over pulleys or sheaves (not shown) in the valance box. These cords pass through somewhat elongated openings 23 in the individual slats substantially larger than the diameter of the cord and are fastened to a conventional bottom member (not shown) beneath the lowest slat.

For the purpose of permitting the slats to be tilted to a completely closed position whereby the slats engage each other, I provide each slat with a cord-receiving recess 25 in the convex portion of its upper surface between the edge of the slat and each opening 23. Also, each slat is provided with a recess 26 in the convex portion of its under surface adjacent each opening 23 and extending therefrom to a recessed edge portion 27 at the outer edge of the slat. The recesses 25 and 26 are sufficiently deep to receive the lift cords. Thus, with this construction, when the individual slats are tilted, as shown in Fig. 4, the lift cords are accommodated in the recesses 25 and 26 and consequently the slats can tilt sufficiently to engage each other in the regions 28 adjacent their margins to thereby provide a substantially light-tight closure. Preferably, the supporting tapes on the inner or room side of the blind are pre-shrunk to insure full closure of the blind.

One feature of my invention is the provision of longitudinally extending reinforcing ribs 30 in the region of the recesses 26 and a reinforcing rib 31 along the outer margin of the slat across each recess 25. These ribs are stamped or otherwise formed directly from the material by shaping it to the configuration best shown in Figs. 2, 5, and 6. I contemplate that such reinforcing ribs can be utilized in other slats, that is, slats which do not embody the recesses 26 and 27 and which may be of other cross-sectional shapes.

Another feature is the provision of the recessed edge portions 27 at the outer edges of the slats. These accommodate the outer supporting tapes 16 as well as the ladder or cross tapes when the blinds are tilted upwardly to closed position as shown in Fig. 4. However, if desired, the recesses need only be deep enough to accommodate the ladder tapes.

In place of the recessed edge construction 27 I may provide merely a pair of T-slots 35 in each slat 15' adjacent the edge of the slat through which the ladder straps are threaded. With this construction, the slats 35 can also be tilted to a completely closed position. In this connection it should be noted that although two T-slots are shown at each location, this is for convenience of manufacture and assembly. The reason for this is that conventional blinds only have one ladder tape at each location, but the tapes are usually alternately staggered on opposite sides of the lift cord. Unless two T-slots are provided at each location it would be necessary to stagger the T-slots in alternate slats, except, of course, in such blinds as provide ladder straps on one side only of the lift cord.

I also contemplate that the blind slats may be made of or embody a magnetic material which is so magnetized that, when the slats are tilted to closed position, the lateral margins of adjacent slats will be magnetically attracted to each other thereby providing a releasable means for holding the slats in engagement in the fully

tilted or closed position. Thus the lateral margins of the slats, or at least portions thereof should have a magnetic polarity opposite to each other. This feature, of course, is applicable to blinds of various cross-sectional shapes.

Although I have illustrated and described preferred forms of my invention, I contemplate that various changes and modifications can be made therein without departing from the invention, the scope of which is indicated by the following claims.

I claim:

1. A Venetian blind assembly, comprising a supporting structure, slat-supporting means depending from said structure, a plurality of slats carried in vertically spaced relation on said slat-supporting means, and means for adjusting said slat-supporting means to vary the angle of disposition of the slats, said slats embodying magnetic material and being magnetized in a manner such that adjacent lateral margins of said slats are magnetically attracted to each other when the slats are tilted to a closed position whereby said slats releasably engage each other when so tilted.

2. In a Venetian blind assembly, a plurality of laterally spaced blind slats, and means for supporting said slats and adjustably pivoting them about individual axes, said slats being formed in part at least of magnetic material and being magnetized in a manner such that adjacent lateral margins of said slats are magnetically attracted to each other when the slats are pivoted to a closed position whereby said slats releasably engage each other when so pivoted.
